(57) **CLAIM**

I claim the ornamental design for a seat for paddle craft, as shown and described.

DESCRIPTION

FIG. 1 is a front isometric view of a seat for paddle craft showing my new design;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

A view of the design bottom side has been omitted, as the bottom of the design is flat and devoid of surface ornamentation.
